United States Patent Office

Des. 227,354
Patented June 19, 1973

227,354

UTILITY BUILDING

Donald Michael Genaro, Haworth, N.J., and Gordon Elliott Sylvester, Jamaica, N.Y., assignors to Bell Telephone Laboratories, Incorporated, Murray Hill, N.J.

Filed Dec. 29, 1971, Ser. No. 213,792

Term of patent 14 years

Int. Cl. D25—03

U.S. Cl. D13—1 R

FIG. 1

FIG. 2

FIG. 3

FIG. 4

FIG. 1 is a perspective view of the front and left side of a utility building embodying our new design;

FIG. 2 is a front elevation of the utility building shown in FIG. 1;

FIG. 3 is a rear elevation of the utility building shown in FIG. 1; and

FIG. 4 is a side elevation of the utility building shown in FIG. 1.

We claim:

The ornamental design for a utility building, substantially as shown and described.
